UNITED STATES PATENT OFFICE.

CURTIS A. CLOYED, OF CEDAR VALE, KANSAS.

CRANK ATTACHMENT.

1,270,007.

Specification of Letters Patent. Patented June 18, 1918.

Application filed December 3, 1917. Serial No. 205,160.

To all whom it may concern:

Be it known that I, CURTIS A. CLOYED, a citizen of the United States, residing at Cedar Vale, in the county of Chautauqua 5 and State of Kansas, have invented certain new and useful Improvements in Crank Attachments, of which the following is a specification, reference being had to the accompanying drawings.

10 This invention relates to certain improvements in crank attachments for internal combustion engines and has relation more particularly to a device of this general character especially designed and adapted for 15 use in connection with motor driven vehicles, and it is an object of the invention to provide a novel and improved attachment which serves effectively to prevent the fly-back of a starting crank of an internal combustion 20 engine upon back fire of said engine or from any other cause.

The invention consists in the details of construction and in the combination and arrangement of the several parts of my improved crank attachment whereby certain 25 important advantages are attained and the device rendered simpler, less expensive and otherwise more convenient and advantageous for use, as will be hereinafter more 30 fully set forth.

The novel features of my invention will hereinafter be definitely claimed.

In order that my invention may be the better understood, I will now proceed to 35 describe the same with reference to the accompanying drawings, wherein:

Figure 1 is a fragmentary view partly in elevation and partly in section illustrating a crank attachment constructed in accordance with an embodiment of my invention;

Fig. 2 is a fragmentary view in top plan of my improvement as herein embodied; and

Fig. 3 is a fragmentary view partly in elevation and partly in cross section, 45 through the frame included in my attachment as herein disclosed.

As disclosed in the accompanying drawings, F denotes the forward transverse beam of a motor driven vehicle frame or chassis 50 herein disclosed as a type employed on the well-known Ford car. B denotes a bearing for the starting crank C which is held in applied position upon the beam F through the medium of the upwardly directed clamping members M substantially U-shaped in form and which are disposed through the

laterally directed ears 1 carried by the base portion of the bearing B.

My improved attachment comprises two vertically disposed plates 2 having their upper marginal portions connected by the interposed web 3 affording a frame substantially in the form of an inverted U. Overlying the upper or outer face of the web 3 is a rigid strap 4 preferably of metal which has its opposite end portions 5 extended beyond the ends of the web 3 and disposed downwardly on a predetermined inclination and provided with the perforate terminals 7 through which the free end portions of the 70 forward arms of the clamping members M are adapted to be directed. The lower marginal portions of the plates 2 adjacent the opposite sides or vertical margins thereof are connected by the rivets 8 or the like with 75 which are pivotally engaged the rigid members or straps 9 which are adapted to extend in opposite direction and provided with the perforate terminals 10 through which the extremities of the arms of the clamping 80 members M are also adapted to be disposed. By this arrangement it will be perceived that the plates 2 may be readily and conveniently put in applied position.

The plates 2 are provided with aligned 85 openings 11 through which the shaft 12 of the starting crank is loosely directed. The shaft 12 is provided with a longitudinally disposed groove or channel 14 extending substantially the entire length thereof and 90 open at the inner end or free end of said shaft. The shaft 12 is also loosely directed through the axial center of a ratchet wheel 15 positioned between the plates 2. The ratchet wheel 15 is provided with a key 16 95 extending within the groove or channel 14 whereby it will be perceived that the ratchet wheel 15 will turn in unison with the shaft 12 but permits longitudinal movement of the shaft 12 independently of the ratchet 100 wheel 15.

The upper end portions of the plates 2 are connected by the rivets 17 in preferably transverse alignment and positioned at opposite sides of the vertical center of the 105 shaft 12. Positioned between the plates 2 and pivotally engaged with the rivets 17 are the gravity pawls 19 of a conventional construction and which coact with the ratchet wheel in a manner to prevent rotation of the shaft 12 in one direction or in 110 a direction opposite to the direction of ro-

tation of the shaft 12 in starting the motor. It will therefore be self-evident that a fly-back of the crank C will be effectively prevented in the event of a back fire of the motor or from any other cause so that the possibility of injury to a person starting or cranking the motor is eliminated.

The ratchet wheel 15 can readily be applied between the plates 2 by swinging one of the pawls 19 and an adjacent member 9 in opposite directions.

From the foregoing description, it is thought to be obvious that a crank attachment constructed in accordance with my invention is particularly well adapted for use by reason of the convenience and facility with which it may be assembled and operated and it will also be obvious that my invention is susceptible of some changes and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with the shaft of a starting crank of an internal combustion engine and a beam arranged transversely of said shaft, a safety attachment comprising a frame substantially in the form of an inverted U, side members of the frame being provided with openings through which the shaft is loosely directed, a ratchet wheel arranged within the frame and through which the shaft is disposed, said shaft being provided with a channel disposed longitudinally thereof and the ratchet being

provided with a key extending within the channel of the shaft, arms secured to the upper portion of the frame and extending beyond opposite sides thereof, members interposed between and supported by the lower end portions of the side members of the frame, oppositely directed arms pivotally engaged with said members, anchoring members carried by the arms and positioned at opposite sides of the shaft, the pair of arms extending from each side of the frame being engaged with one of the anchoring members.

2. In combination with the shaft of a starting crank of an internal combustion engine provided with a channel disposed longitudinally thereof, a safety attachment comprising two plates in fixed relative spaced relation and provided with aligned openings through which the shaft of the crank is loosely directed, a ratchet wheel positioned between the plates and through which the shaft of the crank is also loosely directed, said ratchet wheel being provided with a key extending within the channel of the shaft of the crank, supporting members carried by the opposite end portions of the plates and extending beyond opposite sides thereof, and a pawl supported by the plates and coacting with the ratchet wheel, certain of said supporting members being capable of pivotal movement relative to the plates.

In testimony whereof I hereunto affix my signature in the presence of two witnesses.

CURTIS A. CLOYED.
